UNITED STATES PATENT OFFICE.

PAUL COTA AND WALTER COTA, OF LANGDON, ALBERTA, CANADA.

SHOCKING-MACHINE.

1,130,799.

Specification of Letters Patent. Patented Mar. 9, 1915.

Application filed March 19, 1914. Serial No. 825,865.

To all whom it may concern:

Be it known that we, PAUL COTA and WALTER COTA, both of the town of Langdon, in the Province of Alberta, Canada, have invented certain new and useful Improvements in Shocking-Machines, of which the following is the specification.

The invention relates to improvements in shocking machines and the object of the invention is to provide a machine which can be attached to a binding machine and will receive the sheaves deposited from the binder deck, elevate them, form them into a shock and deposit them butts down on the ground, the complete operation occurring as the machine advances with the binder.

A further object of the invention is to provide a shocking machine which is entirely automatic in its operation requiring no attention by an attendant to effect the dumping or resetting of the basket.

A still further object of the invention is to provide an improved form of basket wherein the sheaves are properly compressed before dumping to spread the butts and thereby give the deposited shock a substantial base to stand on.

A still further object of the invention is to provide a basket which will open freely when it has reached the dumping position to release the shock and which will have no tendency to upset the shock as the machine passes away from the same.

With the above objects in view the invention consists essentially in the arrangement and construction of parts hereinafter more particularly described and later pointed out in the appended claims.

Figure 1 is a front view of the shocking machine connected to a binding machine. Fig. 2 is a plan view of the same. Fig. 3 is a side view of the machine. Fig. 4 is an enlarged detailed vertical sectional view through the basket, the section being taken in the plane denoted by the line X—X'. Fig. 5 is an enlarged detailed longitudinal sectional view through the collars and adjoining parts on the auxiliary shaft. Fig. 6 is a side view of the sleeve, and lever mounted on the auxiliary shaft, adjoining parts being shown in vertical section. Fig. 7 is a face view of the chain wheel. Fig. 8 is a sectional view through the butting plate and a portion of the basket frame showing the trip bar engaging with the lever. Fig.

9 is a perspective view of one of the forward corners of the basket frame showing the trip bar. Fig. 10 is a vertical sectional view through the top of the basket showing the pressure bar in section. Fig. 11 is an interior view of a portion of one side of the basket showing the mounting of the pressure arm. Fig. 12 is a perspective view of the machine frame. Fig. 13 is an enlarged detailed vertical sectional view through the counter shaft, showing the pin, sleeve and adjoining parts in side elevation.

In the drawings like characters of reference indicate corresponding parts in each figure.

At the onset it will be understood that our machine can be attached to any binder and in order that the manner in which it is attached may be completely understood we have considered it advisable to show and refer to the following parts of the binder.

1 represents a binding machine frame, 2 the master wheel thereof, 3 the elevator, and 4 the deck, the deck being designed to receive and eject the sheaves passed from the elevator as is customary.

7 is a shocking machine frame which is pivotally connected to the binder frame at the inner side and has the outer side carried by a carriage wheel 8.

The frame is formed from the following members: 9 and 10 are two similar cross bars having the body portions thereof permanently bolted together, the inner ends spread apart in a Y-shaped manner and the outer ends bent at right angles to the body portions and extending rearwardly at some distance apart. 11 is a brace bar having the ends thereof permanently connected to the inner and outer ends of the beam 10. 12 and 13 are a pair of similar more or less vertically disposed and opposing side bars bent substantially in a U-shaped manner and permanently secured by suitable bolts to the bar 9. The U-bars are connected by an upper cross bar 14. The inner end of the frame, that is the inner ends of the bars 9 and 10, is pivotally connected by bolts 15 to a pair of hangers 16 secured permanently forwardly and backwardly to the binder frame. The back-turned extremities of the bars 9 and 10 receive between them the carriage wheel 8 already referred to, which is carried by a drive shaft 17 having the ends thereof mounted in suitable bearings pre-

sented by the ends of the said bars. 18 is a sheaf receiving and shock forming basket. The construction of the basket is now described: 19 and 20 are a pair of similar rearwardly converging side bars connected forwardly by an upwardly directed yoke bar 21 and rearwardly by a downturned yoke bar 22 the latter bar being spanned by a sheet metal head plate 23. The side bars 10 are pivotally mounted more or less centrally of their length on pivot bolts 24 and 25 presented by the U-bars. 26 and 27 are a pair of complementary gates having their upper edges connected by hinges 28 to the under 15 sides of the bars 19 and 20. 29 is the top of the basket secured at one side by hinges 30 to the upper sides of the bars 19 and 20. The gates and top are shaped so that the basket body is normally more or less circular in cross section at any point which section gradually diminishes in passing from the front to the back. Spiral springs 31 are embodied in the hinges 30 which springs have a constant tendency to hold the top up 20 in a set position and provide an entrance opening in the side of the basket at 32 immediately adjoining the deck of the binder. The gates are provided on the under side with extending foot pieces 33 and 34 which 25 foot pieces are designed to rest against the vertically disposed portions of the U-bars and hold the gates up when the basket is in the normal or horizontal position. These foot pieces are arranged also to ride, when 30 the basket is dumped, on permanent guide bars 35 and 36 secured to the U-bars. These guide bars are turned gradually outwardly from the basket and are bent concentric to the pivot bolts 24 and 25 so that the gates 35 are gradually allowed to open as the basket is dumped as later explained. 37 is a pressure bar carried by the inner side of the top of the basket and toward the rear end thereof. The pressure bar is formed from spring 40 metal and has one end thereof permanently secured by rivets 37' to the basket top and the other end thereof fitted with a projecting pin 38 which passes slidably through a slot provided in the top. The spring material from which this bar is made causes it 45 to press the pin fully within the hole under normal conditions. However upon pressure being brought to bear on the body of the bar it will spring back, the pin withdrawing to 50 accommodate the movement. 39 is a pivoted pressure arm contained within the basket and carried by the bar 20 at a point behind the pivot bolt 25. This arm is mounted pivotally on a pin 39' carried by a small bracket 39² secured to the inner side of the bar. A spring 39⁰ is coiled on the pin and has the extremities extending and bearing one against the inner face of the bar 20 and the other bearing against the upper face of 55 the arm. Accordingly the tendency of the

spring is to continuously press the arm downwardly.

We wish now to draw particular attention to the lower end of the arm which it will be noticed is bent outwardly at a point beneath the pivot pin to form a trip 39^x located normally immediately at the under side of the bar 20 and immediately above a permanent catch bar 12^x suitably secured to the U-bar 12. This arrangement is such that 70 when the forward end of the basket is swung upwardly from the dumping position the trip rides over the face of the catch bar and then springs in above the free edge of the bar with the result that the basket is locked against dumping until the said trip is released from the catch bar by the upward movement of the pressure arm under the action of the sheaves as later described. In connection with this pressure arm it is remarked that after it is once released from the catch plate in the dumping of the basket it presses down on the sheaves and holds them tightly against the gates, the pressure being effected by the spring 39⁰. 75 80 85 90

41 is a permanent butting plate located at the front end of the basket and carried by the shocking machine frame. This plate is arranged so that it actually closes the forward end of the basket but is entirely free of the same to allow the basket to operate. The butting plate carries a centrally disposed more or less V-shaped dividing block 41' on its lower edge which is designed to split and spread the butts of the sheaves as 100 the basket turns to the dumping position.

42 is a pressure rod having one end pivotally secured at 42' to the upper edge of the butting plate and the other end hooked and slidably received within a slot 43' formed 105 in a guide bar 43 secured to the upper side of the basket top. The arrangement is such that the hook is in the forward end of the slot when the basket is in the receiving position and reaches the opposite or rear end of the slot at a time prior to the basket assuming the dumping position with the result that the basket top is forced or sprung in on the hinges to follow up the shock practically at the instant the gates are released. 110 115

44 is a counter shaft rotatably mounted in suitable brackets 45 and 46 secured to the sides of the butting plate.

47 is a chain wheel permanently mounted on the drive shaft 17 and connected through 120 a chain 48 with a chain wheel 49 freely mounted on the counter shaft. The latter chain wheel is supplied with a sleeve 49' fitted with teeth designed in the forward rotation of the wheel to engage with the 125 protruding ends of a pin 50 carried by the counter shaft and in the reverse rotation of the wheel to slip past the pin. A spiral spring 51 is mounted on the shaft between the chain wheel 49 and a bracket 52 receiv- 130

ing the end of the counter shaft and carried by the frame. The spring is designed to press the teeth continuously against the pin.

In order that the teeth may be entirely withdrawn from the pin against the action of the spring we have supplied a shifting rod 53 which has the inner end thereof connected to the sleeve and the outer end slidably mounted in a slot formed in a standard 54 carried by the bracket 52.

The under side of the rod is provided with an extending lug or catch 53' arranged to slide with the rod within the slot and engage the outer face of the standard. In this 15 way by pulling the rod out and engaging the catch with the face of the standard after it has escaped from the slot it is possible to entirely withdraw the teeth of the sleeve away from the pin with the result that the 20 counter shaft will not rotate although the chain may be driving the chain wheel 49.

55 is an auxiliary shaft parallel with the counter shaft and mounted in the upper ends of the brackets 45 and 46. The auxiliary shaft has the ends thereof formed into cranks 55' and 55² which cranks carry connecting links 56 and 56' having their rear ends pivotally fastened to downturned actuating arms 57 and 57' having the body 25 portions thereof mounted on the pivot bolts 24 and 25 and the rear ends thereof permanently fastened to the bars 19 and 20 of the basket frame.

58 is a chain wheel fixed on the counter 35 shaft and connected through a chain 59 with a chain wheel 60 rotatably mounted on the auxiliary shaft and located between a pair of collars 61 and 62 fast to the shaft.

63 is a spring pressed sleeve freely mounted 40 on the auxiliary shaft and adjoining the collar 62. The sleeve carries a locking pin 64 which passes slidably through a suitable opening formed in the collar and protrudes normally into one or other of a series of concentrically arranged openings 65 provided in the chain wheel 60.

66 is a controlling lever pivotally secured to the cross bar 14 and having the lower end thereof fitted with a slot 66' receiving a 50 pin 67' extending from the face of a ring 67 mounted in a suitable groove provided in the face of the sleeve 63. The upper end of the lever is turned inwardly through a slot 68 appearing in the butting plate and located 55 immediately adjoining a trip bar 69 permanently secured to the basket frame.

The arrangement of the trip bar in relation to the lever in the normal or sheaf receiving position of the basket is such that 60 the lever is held over against the action of the spring in a position such that the sleeve is withdrawn from the face of the collar 62. Accordingly the pin 64 is entirely withdrawn from the chain wheel 60 to allow the 65 wheel to rotate freely without driving the

auxiliary shaft. In this connection it is remarked that as soon as the basket is freed to dump by the releasing of the trip 39^x, the trip bar passes away with the basket from the inturned end of the lever which springs 70 over and accordingly actuates the pin to couple up the chain wheel 60 with the auxiliary shaft.

70 is an inclined conveyer carried by the shocking machine frame and disposed between the deck of the binder and the basket, the conveyer being arranged and operated to receive sheaves from the deck and deposit them through the opening 32 into the basket. This elevator is formed from side pieces 71 80 and 72 carrying upper and lower conveyer shafts 73 and 74 on which we have mounted pairs of chain wheels 75 carrying chains 76 provided with cross slats 77 fitted with extending prongs 78.

79 is a hanger having one end permanently secured to the butting plate and the opposite end pivotally secured to the upper end of the conveyer and 80 is a bracket having one end permanently secured to a brace 90 bar 81 extending angularly between the bar 9 and the U-bar 13 and the other end connected by a pivot pin to the opposite side of the conveyer. In this way the conveyer is mounted so that the lower end can be ad- 95 justed or swung in respect to the deck.

82 and 83 are adjusting bars secured respectively to the conveyer and to the shocking machine frame and having their adjoining ends provided with a series of adjusting openings which receive an adjusting pin 84.

85 is a shield secured to one side of the conveyer and also to the butting plate.

86 is an ejector shaft provided with a 105 large crank 86' located directly above the upper end of the conveyer, the forward end of the ejector shaft being rotatably mounted in a bracket 87 carried by the butting plate and the rear end of the shaft being 110 received within an upper extension of the bracket 80.

88 is a guard swung freely from the ejector shaft and located above the conveyer. It is to be noticed that this guard is formed 115 from a pair of side bars 88' and 88² connected by a connecting bar 88^x. The lower ends of the side bars are turned upwardly while the forward end of the connecting bar is extended to rest on the upper edge of the 120 shield.

The inner end of the counter shaft 44 is fitted with a worm wheel 89 which meshes continuously with a worm 90 located on the lower end of an upright shaft 91 having the lower end thereof rotatably mounted in a hanger 92 extending from the bracket 46 and the upper end carried by a bearing 92' secured to the side of the shield.

The forward end of the upper conveyer 130

shaft and the forward end of the ejector shaft are each supplied with worm wheels 93 and 94 arranged to mesh continuously with worms 95 and 96 secured to the upright shaft. In this way the upright shaft forms a drive for the conveyer and the ejector shaft.

In order to prevent the outer end of the shocking machine from falling back when 10 in use it is necessary to connect the outer forward corner thereof with the binder tongue by a tie rod. This tie rod is indicated by the reference numeral 97.

98 is a sheet metal trough located between 15 the lower edge of the deck and the lower edge of the conveyer to which parts it is connected by hooks 98' secured to suitable eyes 99 carried by the conveyer and the deck.

20 In order to better understand the invention we will now describe its operation assuming sheaves are passed over the binder deck in the usual way, the machine advancing with the binder and the basket 25 locked in the sheaf receiving or horizontal position.

In the advancement of the machine the counter shaft 44 is rotated by the chain wheel 47 and in rotating operates the up- 30 right shaft which in turn drives the conveyer and the ejector shaft.

The sheaves delivered from the deck are accordingly picked up by the conveyer and passed into the basket through the opening 35 in the side thereof. As the basket begins to fill with sheaves the ejector shaft materially aids in forcing them into the basket. When sufficient sheaves have been passed to the basket to form a proper shock the basket 40 is automatically dumped by the pressure of the incoming sheaves against the pressure arm 39. It will be seen that as the basket fills the pressure arm will be gradually swung upwardly by the sheaves with the 45 result that the trip 39* is turned downwardly a sufficient amount to release it from the catch bar 12*. As soon as this occurs the forward end of the basket drops sufficiently far to allow the trip bar 69 to pass 50 away from the inturned end of the lever 66. The instant the lever is released the spring on the auxiliary shaft 55 operates to slide the sleeve 63 over with the result that the pin 64 is forced into one or other 55 of the openings in the chain wheel 60. The auxiliary shaft is then completely controlled by the counter shaft so that as the machine advances the counter shaft rotates the auxiliary shaft and accordingly turns the 60 cranks 55' and 55". As the cranks rotate they operate the links to turn the basket to dumping position by virtue of the actuating arms and then return the basket to the initial position in the one revolution of the 65 auxiliary shaft. As the basket is turned to

the dumping position pressure is retained on the sheaves by the pressure bar until the gates swing open, their opening being controlled by the action of the foot pieces 35 and 36 on the guide bars. It is also pointed out that the top of the basket is swung in just prior to the basket assuming the dumping position, this being effected by the rod 42 reaching the end of the slot prior to the instant that the basket takes what might 70 be termed the upended position. As the basket is swung back by the links to the normal or receiving position the trip bar catches the inturned end of the lever 66 and shifts the lever to withdraw the pin from 75 the chain wheel 60 with the result that the auxiliary shaft stops rotating. At the time that this is occurring the out-turned end of the trip 39* is being swept past the catch bar 12* and escaping over the upper edge 80 of the said bar locks the basket against dumping approximately at the instant the pin is withdrawn from the chain wheel. Accordingly the machine advances with the basket until another shock has been built up in the basket at which time the pressure arm will again operate to automatically dump the basket as hereinbefore described.

The guard is supplied to hold the sheaves 95 down on the conveyer and prevent loose straw from blowing with the wind. The shield 85 guides the butts of the sheaves as they are passed over the conveyer.

What we claim as our invention is;

1. The combination with a binding machine and a shocking machine frame having the inner end thereof pivotally secured to the binder frame on the deck side and the outer end thereof mounted on a carriage wheel, of a sheaf receiving and shock forming basket pivotally mounted on the frame, a conveyer carried by the shocker frame and disposed between the binder deck and the basket and designed to elevate the sheaves 100 from the deck and deposit them in the basket, a spring pressed pressure arm pivotally secured to the basket on the side opposing the conveyer, said pressure arm having one end thereof extending upwardly within the 105 basket but clear of the same and the other end extending outwardly beyond the basket in the form of a trip and engaging with the shocker frame and normally locking the basket in the sheaf receiving position said 110 arm having the inner end thereof designed to be actuated by sheaf pressure upon the complete formation of a shock within the basket to release the trip end thereof from the frame and free the basket to dump, a 115 stationary butting plate carried by the frame and adjoining the forward end of the basket, a rotatably mounted counter shaft carried by the shocker frame and normally rotated by the carriage wheel in the ad- 120 125 130

vancement of the machine, an auxiliary shaft mounted on the shocker frame, a chain wheel fixed on the counter shaft, a chain wheel rotatably mounted on the auxiliary shaft and connected through a chain with the latter chain wheel, shiftable spring pressed means for coupling the chain wheel on the auxiliary shaft to the auxiliary shaft, a lever pivotally secured to the butting plate having one end thereof connected with the shiftable coupling means aforesaid and the opposite end turned inwardly through the butting plate toward the basket, a trip bar secured to the forward end of the basket and normally engaging with the lever and normally holding the coupling means disengaged, said trip bar being designed in the unlocking of the basket to free the lever and release the shiftable means to couple the chain wheel to the auxiliary shaft and effect the rotation of the auxiliary shaft with said chain wheel, means actuated by the auxiliary shaft in rotating for dumping the basket and returning the same to the initial position, as and for the purpose specified.

2. The combination with a binding machine and a shocking machine frame having the inner end thereof pivotally secured to the binder frame on the deck side and the outer end thereof mounted on a carriage wheel, of a sheaf receiving and shock forming basket pivotally mounted on the frame, a conveyer carried by the shocker frame and disposed between the binder deck and the basket and designed to elevate the sheaves from the deck and deposit them in the basket, a spring pressed pressure arm pivotally secured to the basket on the side opposing the conveyer, said pressure arm having one end thereof extending upwardly within the basket but clear of the same and the other end extending outwardly beyond the basket in the form of a trip and engaging with the shocker frame and normally locking the basket in the sheaf receiving position, said arm having the inner end thereof designed to be actuated by sheaf pressure upon the complete formation of a shock within the basket to release the trip end thereof from the frame and free the basket to dump, a stationary butting plate carried by the frame and adjoining the forward end of the basket, a rotatably mounted counter shaft carried by the shocker frame, a drive connection between the carriage wheel and the counter shaft, a drive connection between the counter shaft and the conveyer, an auxiliary shaft mounted on the shocker frame and parallel with the counter shaft, a chain wheel fixed on the counter shaft, a chain wheel freely mounted on the auxiliary shaft and operating between a pair of collars fixed to the auxiliary shaft, said latter chain wheel being provided with a series of concentrically arranged openings, a chain connecting the chain wheels, a spring pressed sleeve mounted on the auxiliary shaft and adjoining one of the collars, a pin extending from the sleeve slidably into the adjoining collar and designed to pass into one or other of the openings in the chain wheel, a lever pivotally secured to the butting plate and having one end thereof connected with the sleeve and the opposite end thereof turned inwardly through the butting plate toward the basket, a trip bar secured permanently to the forward end of the basket and engaging normally with the lever and retaining the same normally in a position such that the pin is free of the chain wheel, said trip bar being designed in the unlocking of the basket to pass away from the lever and thereby free the pin to pass under the action of the spring into the chain wheel and effect the rotation of the auxiliary shaft with the counter shaft, cranks located at the ends of the auxiliary shaft, actuating arms extending from the basket and links connecting the actuating arms with the cranks, as and for the purpose specified.

3. The combination with a binding machine and a shocking machine frame having the inner end thereof connected to the binding machine and the outer end pivotally mounted on a carriage wheel, of a sheaf receiving and shock forming basket pivotally carried by the shocker frame and comprising an opposing pair of converging side bars secured by opposing pivot pins to the frame, a pair of normally closed gates forming the bottom of the basket, said gates being hinged to the side bars, out-turned guide bars secured to the shocker frame and arranged concentric to the pivot pins, foot pieces extending from the under side of the gates and riding on the guide bars, said foot pieces holding the gates closed in the formation of the shock within the basket, a normally open top hinged to one of the cross bars, a stationary butting plate closing the forward end of the basket and carried by the shocker frame, automatically operated means actuated by the carriage wheel for upending the basket to dump the shock and returning the same to the initial position, a pressure rod pivotally connected to the butting plate and provided with a hooked end, a slotted guide bar secured to the top of the basket and receiving the hooked end of the rod, said pressure rod being designed to effect the closing in of the top of the basket in the dumping position thereof, as and for the purpose specified.

4. In a shocking machine the combination with a pivoted basket provided with a hinged top, of a pressure bar located on the inner side of the top and having one end permanently secured to the top and the

other end thereof provided with an extending pin slidably received within the top, as and for the purpose specified.

5. The combination with a binding machine, a shocking machine frame having the inner end thereof pivotally connected to the binder frame and the outer end thereof pivotally mounted on a carriage wheel, a sheaf receiving and shock forming basket 10 pivotally carried by the frame and having an opening in the side thereof toward the binder and an inclined conveyer carried by the shocker frame and designed to receive sheaves from the binder deck, elevate them 15 and deposit them in the basket, of a rotatably mounted elevated ejector shaft passing across the upper end of the conveyer and provided with a centrally disposed crank and means actuated by the carriage wheel for rotating the ejector shaft, as and for the purpose specified.

6. The combination with a binding machine, a shocking machine frame having the inner end thereof pivotally connected to the binder frame and the outer end thereof 25

pivotsly mounted on a carriage wheel, a sheaf receiving and shock forming basket pivotally carried by the frame and having an opening in the side thereof toward the binder and an inclined conveyer carried by 30 the shocker frame and designed to receive sheaves from the binder deck, elevate them and deposit them in the basket, of a rotatably mounted elevated ejector shaft passing across the upper end of the elevator and 35 provided with a central crank, means actuated by the carriage wheel for rotating the ejector shaft, a shield secured to the side of the elevator and a guard pivotally mounted on the ejector shaft and having one end 40 thereof normally resting on the shield, as and for the purpose specified.

Signed at Griesbach P. O. this 30 day of December 1913.
